G. S. THOMPSON.
DEVICE FOR TREATING SURGICAL WOUNDS.
APPLICATION FILED JULY 29, 1919.

1,405,355.

Patented Jan. 31, 1922.

Fred Walsh

UNITED STATES PATENT OFFICE.

GEORGE STANLEY THOMPSON, OF RANDWICK, NEAR SYDNEY, NEW SOUTH WALES,
AUSTRALIA.

DEVICE FOR TREATING SURGICAL WOUNDS.

1,405,355.

Specification of Letters Patent. Patented Jan. 31, 1922.

Application filed July 29, 1919. Serial No. 314,167.

(GRANTED UNDER THE PROVISIONS OF THE ACT OF MARCH 3, 1921, 41 STAT. L., 1313.)

To all whom it may concern:

Be it known that I, GEORGE STANLEY THOMPSON, a subject of the King of Great Britain, residing at "Glenelg" Carr Street, 5 Randwick, near Sydney, in the State of New South Wales, in the Commonwealth of Australia, have invented a new and useful Improvement in and Relating to a Device for Treating Surgical Wounds, (for 10 which I have filed application in Australia, June 27, 1918, Patent No. 7817/18,) of which the following is a specification.

Heretofore in the treatment of wounds in the human body the fluids discharging therefrom whether physiological (e. g. bile, digestive juices and the like) or pathological (e. g. discharges from cysts and the like and particularly matter from abscesses) have been allowed to be absorbed by the 15 dressings of the wounds or incisions. These dressings however get quickly saturated with the irritating and poisonous discharge (which in the case of pus rapidly coagulates and presents an impenetrable 20 barrier to further absorption) and which thus cannot be further imbibed and is consequently dammed or held back by the dressing. Hence a virtually foul pus-poultice very soon takes the place of what was 25 a clean dressing. The discharge being unable to escape (the parts becoming bathed in foul pus which wells up on removal of dressing) it undermines the wound, causes its dangerous extension, besides being 30 absorbed into the blood and so inviting the serious danger of blood poisoning.

Now this invention has been specially devised in order to obtain perfect drainage of the wound in a comparatively short 35 time, to eliminate the necessity of repeated dressing of the wound resulting in much saving of attention and labor and of material to enable a desired function to be performed by an incision of considerably reduced size resulting in an almost invisible 40 scar on recovery and also to prevent damping back of the discharge with consequent undermining extension of mischief and danger of blood poisoning, of pus poultices 45 and of foul discharge necessitating bathing and irritation of skin and further to achieve a rapid change of pus to serum (replacing 50 a long suppurative discharge) and a consequent rapid healing of lesion.

Improved treatment of wounds according 55 to this invention comprises the application surrounding or exteriorly of the wound of a collecting cup adapted to have comfortable contact with the area of the body surrounding the wound and having an orifice 60 or a number of orifices to render said collecting cup serviceable for almost any site on the body to one of which orifices while the others are plugged a bendable discharge tube (say of rubber) is connected as it 65 also is to a receiving vessel or bottle by insertion therein through a removable cap with a pin hole vent therethrough and further the attachment to the body of the cup with the discharge tube and receiving vessel or bottle free by anti-septic adhesive 70 plaster with bandage thereover.

In a modification of this improved treatment in the case of special wounds such as 75 an incision of an abscess a cannula inserted into the cavity by means of a trocar is substituted for the collecting cup and to the external end of the cannula the discharge tube is connected and has at its free end 80 the receiving bottle before mentioned.

In a further modification of this improved treatment in the case of wounds on the finger or the penis for which being elongated parts of the body the cup before mentioned is 85 unsuitable for casing or loose stall preferably of rubber is substituted for the cup and it preferably has an elastic neck ring and in the finger casing a junction orifice for the discharge tube near the neck and in the penis casing such as orifice at the closed 90 end.

The invention is clearly illustrated in the accompanying drawings, in which—

Figure 1 is a side elevation of the preferred form of the invention applied to a 95 wound;

Fig. 2 is a similar view of another form of the invention;

Fig. 3 is an elevational view of still another form of the invention;

Fig. 4 is an elevational view of a modified form of a receiving receptacle;

Fig. 5 is a cross sectional detailed view of the cup used in the preferred form;

Fig. 6 is a longitudinal section detail 105 thereof;

Fig. 7 is an elevational detail looking toward the inside of the cup;

Fig. 8 is a sectional view of another form of the invention; and

Fig. 9 is a similar view of another form of the invention.

Referring now, more particularly, to the accompanying drawings there is illustrated the treatment of an incised wound wherein the body 11 has a cavity 12 to be drained by means of a draining pipe 13. On the 10 wound is positioned the collecting cup 14 secured to the body by antiseptic plaster 15. A cord or thread 31 is passed through the pipe 13 reaching to and under two opposed edge faces of the cup 14 and is thus so held 15 that no movement is allowed to it in the wound. This cup is described in detail with reference to Figs. 5, 6, and 7 and from it a discharge tube 16 leads to a receiving vessel or bottle 17. It will be seen the 20 wound cavity 12 drains through pipe 13 into the cup 14 which by reason of the securing plaster 15 firmly holding it makes a liquid tight joint on the body 11. The collected contents of the cup flow through tube 16 25 into the bottle 17 from which the contents may be withdrawn as often as desired.

The cup 14, for the preferred form, is shown in detail in Figs. 5, 6 and 7 and preferably is constructed of antiseptic 30 metal, such as iron, silver, aluminum or the like, but may be of glass, the shell being made as light as possible and internally as smooth as possible, with also a smooth facing. This cup is provided with three 35 orifices so as to make it universal or suitable for use in all positions. The orifice 22 is at the top and the orifice 23 at the end and both of these are shown as plugged while the orifice 24 at the side is provided with a 40 rimmed thimble whose verging rim 25 bears against the internal edge of the orifice and a screwed sleeve 27 on its external threaded end makes the joint tight while the rubber tube 16 is arranged over the exposed 45 end of the sleeve 27. Though the most approved construction of this cup is adopted it may be made of various shapes and have just such orifices as may be most suitable.

50 In Fig. 2 there is shown a modified form of the invention illustrating the treatment of a body wound for the purpose of relieving an abscess and in which the boat 14 is replaced by a longitudinal collecting vessel. The body 11 is incised through to the abscess cavity 12 by means of a trocar-cannula 55 to the cannula 14^a of which the trocar having been withdrawn is screwed or fitted an adapter tube 18 say of metal on which is 60 affixed the tube 16 to receiving vessel or bottle 17. In this case the retained cannula 14^a in the incision serves the dual purpose of the drainer pipe 13 and the cup 14 of Fig. 1 and insures the same effect and efficiency in regard to the draining of the

cavity 12. The cannula is held in place in any suitable manner but preferably a washer 32 of celluloid is fast fitted over it and this washer is held to the body by means of tape or adhesive plaster 15.

70 In the form shown in Fig. 3 for the treatment of a finger wherein for the collecting cup a rubber casing or stall 19 is substituted and this casing has an orifice midway of its length as shown in section in Fig. 8 for attachment thereto of tube 16 to bottle 17. The mouth of this casing 19 should be contractile and preferably it is made with an expansible neck 19^a so that it will fit comfortably tightly on the finger while in use 80 as the drainings of the wound get away as before described with reference to other figures of the drawing.

In Fig. 4 is shown a modified form in connection of the tube 16 with the bottle 85 17 (in this case shown flask shape) the orifice in the screw-on-cover 20 of which is slightly smaller than the outer diameter of said tube and so holds the latter firmly. And said cover 20 has a small vent orifice 90 21 to provide for the escape of air from the bottle which the drainings therein displace.

In the forms of casings shown in Figs. 8 and 9 the first is for the finger having its outlet in its side upwardly of its end and the other for the penis having its outlet 29 at the closed end opposite its mouth. Each of these casings 19 has in its respective orifices (each of which is protected by a metal eyelet 30) the thimble 26 with verging rim 100 25 and the screw sleeve 27 for making a tight joint and for affixing thereto the rubber tube 16 and such casing has also the contracting neck 19^a for tightly affixing it on the subject. The casings may have near 105 their mouth eyeletted orifices 28 to facilitate attachment to the body and this is regarded as recessing for the penis casing.

It is preferable that in the construction of the various parts of the instruments or devices that the same be standardized, i. e., made universal or interchangeable for instance the thimble verging rim and screw sleeve of the jointing should be made to fit the orifices of the cup and thereof all the 115 casings.

What I claim as my invention, and desire to secure by Letters Patent is:—

1. A device for treating surgical and like 120 wounds including a collecting cup adapted to be attached over the wound and provided with a plurality of orifices, an inlet tube supported within the cup and adapted to be arranged within the wound, a flexible discharge tube leading from one of the orifices into the cup, a receiving vessel connected with the lower end of the discharge tube, and plugs for removably closing the 125 uncovered orifices.

2. A device as claimed in claim 1 wherein 130

means are employed for supporting the inlet tube and consists of a thread passing through the tube and adapted to extend across the wound and means for fastening 5 the thread and the cup in position against the body of the patient.

3. A device as claimed in claim 1 wherein an improved means is employed for engaging the cup and flexible tube together consisting of an exteriorly threaded and 10 flanged nipple arranged through the cup with the flanged portion bearing against the

interior of the cup and an interiorly threaded sleeve connected with the discharge tube and removably engageable with the exteriorly threaded portion of the nipple. 15

In testimony whereof I have signed my name to this specification in the presence of two subscribing witnesses.

GEORGE STANLEY THOMPSON.
